DESIGN FOR A BOTTLE

François Klotz, Asnieres, France, assignor to Pinaud Incorporated, New York, N. Y., a corporation of New York

Application May 5, 1938, Serial No. 77,020

Term of patent 14 years

To all whom it may concern:

Be it known that I, François Klotz, a citizen of the French Republic, residing at Asnieres (Seine) France, have invented a new, original, and ornamental Design for a Bottle, of which the following is a specification, reference being had to the accompanying drawing, forming part thereof.

Fig. 1 of the drawing is a front elevation of a bottle, showing my new design;

Fig. 2 is a corresponding side elevation;
Fig. 3 is a corresponding top plan view; and
Fig. 4 is a corresponding bottom plan view.
I claim:

The ornamental design for a bottle, as shown.

FRANÇOIS KLOTZ.
